WIRE CONNECTOR CLAMP

William Lawrence Butler, Hendersonville, N.C., assignor to General Electric Company, a corporation of New York

Filed Dec. 16, 1960, Ser. No. 76,210
8 Claims. (Cl. 339—95)

This invention relates generally to wire connectors and more particularly to a clamp for securing a wire to such a connector.

It is frequently necessary to connect the end of an electrical conductor or wire to some apparatus. Often for these purposes an intermediate member or wire connector is used to make the connection to the apparatus.

An electrically good solderless connection can be made if the oxidation on the wire surface is broken by clamping action or some other method, and this will occur if the edges of a clamp are caused to "bite" into the wire. A clamp, to be practically acceptable, should be simple both in structure and in operation and it should be relatively inexpensive.

Therefore, it is an object of this invention to provide a wire connector clamp which is simple to manufacture.

It is also an object of this invention to provide a wire connector clamp which is easily clamped to a wire.

It is a further object of this invention to provide an inexpensive expendable clamp for a wire connector.

Briefly stated, in carrying out the invention in one form which may be preferred, a wire connector clamp is arranged to comprise three plate members joined along one edge so as to form acute dihedral angles between adjacent plate surfaces. The central plate extends from the junction of these plates a greater distance than the other two plates and is provided with a wire receiving aperture having its center located at a point displaced from the junction approximately the same distance as the ends of the other plates are from the junction. In use, a wire is placed through the aperture in the central plate and thereafter the outer plates are biased to overlie the central plate thereby causing the outer plates to "bite" into and clamp the wire to hold it fast. The clamp may be secured to a wire connector or other desired apparatus, either by the same device used to bias the plates together, or by some other means.

The invention will be better understood from the following description taken in connection with the accompanying drawings, in which the FIG. 1 is an exploded perspective view of a wire connector clamp according to the invention; FIG. 2 is a view in section illustrating the clamp of FIG. 1 to a terminal plate; and FIG. 3 is a modification.

Referring now to the drawing, and particularly to FIG. 1, a wire 1 is shown which may be electrically connected to the metal bar 2 that represents some portion of a wire connector or apparatus terminal member. This connection can be accomplished by using the clamp 3, of the invention, which may be bent from an elongated plate into the substantially psi-shaped cross-section shown. As shown, the inner two legs 4 and 5 are folded until their adjacent surfaces overlie in contact with each other to form essentially a single plate member generally shown at 20. The outer two legs 6 and 7 are folded so as to make acute dihedral angles with the opposing plane surfaces of the inner leg 20. The apexes 8 and 9 respectively of the two acute dihedral angles may be positioned so as to provide a substantially common junction of the legs 4, 5, 6 and 7 along one edge thereof. This common positioning of the apexes is convenient for purposes of description and may facilitate the manufacturing of the clamps, but it is not essential to the in-

2

vention since, for example, either apex 8 or 9 may be located at a different relative position.

As the drawing shows, the outer legs 6 and 7 extend a shorter distance from the apexes 8 and 9 respectively than does the central leg 20. A wire receiving aperture 10 passes through the inner leg 20 with its center at such a point that the ends 11 and 12 respectively of the outer legs 6 and 7 partially overlie the aperture 10 when the legs 6 and 7 are brought together in substantially flatwise relation with the central plate 20. Preferably the center of the aperture 10 is generally in alignment with or slightly beyond the ends 11 and 12 of the legs 6 and 7 and the aperture has a diameter just slightly larger than that of the wire expected to be held by the clamp. As is further shown by the drawings, an aperture 13 in the leg 6, a similar aperture 14 in the leg 7, and an aperture 15 passing through the center leg 20 are provided. The last mentioned apertures 13, 14 and 15 are made large enough to receive a fastener 16 or the like in a manner to be later described, and may be designated as fastener receiving apertures.

As the drawing shows, a headed fastener such as the threaded screw 16 is provided having a threaded shank portion 17. The screw 16 serves to secure the clamp 3 to the metal bar 2 which therefore may be provided with an internally threaded aperture 18. In securing the clamp 3 to the metal bar 2, the screw 16 also brings the outer legs 6 and 7 of the clamp into juxtaposition with the inner leg 20. In order to permit the shank 17 of the screw 16 to pass through the apertures 13, 14 and 15 when the clamp 3 is in the position shown, and still not bind the shank when the legs are in juxtaposition, the outer apertures 13 and 14 may be made large enough to be somewhat elliptical as shown. A wire receiving aperture 19 may be provided on the metal bar 2 in a location determined by that of the apertures already described to be in alignment with aperture 10 when the clamp 3 is secured to the connector bar 2 to thereby permit the wire 1 to be passed through both apertures 10 and 19 when clamped.

In use, the end of the wire 1, stripped of any insulation, is inserted into the wire receiving aperture 10 of the clamp 3 and the aperture 19 of the connector bar 2. A screw 16 is then inserted into the apertures 13, 14 and 15, and is then screwed into the internally threaded aperture 18 on the metal bar 2. It is evident that as the screw forces the outer legs 6 and 7 of the clamp towards the inner leg 20 that the ends 11 and 12 of the outer legs 6 and 7 will begin to bite into the wire 1. When the parts are correctly sized, it will be found that the wire 1 is firmly secured in the clamp 3 and to the metal bar 2. Because the ends 11 and 12 of the legs 6 and 7 actually imbed themselves in the metal of the wire 1, a good electrical connection is made and, in fact, it will be found that subsequent removal of the screw 16 will not release the wire 1 from the clamp 3. The end of the wire 1 when once secured to clamp 3 can be moved from one metal bar 2 to another at will without the necessity of utilizing a new clamp. On the other hand, the simple structure of the clamp 3 facilitates mass production of this part with a resulting small unit cost. If, for some reason, it becomes desirable to remove the clamp, it can be clipped off with the end of the wire 1 without substantial financial loss.

Conventional connectors which complete the connection by tightening a screw require the wire to be inserted under the screw in a direction at right angles to the axis of the screw and the screw driver unless the wire is pre-formed or is provided with a previously attached terminal. In completing a connection with the connector of this invention, the wire is inserted in the wire receiving aperture 10 by a longitudinal axial movement parallel

to the axis of the screw driver that is being used to tighten the screw. The importance of this will be recognized when considered in relation to the trend toward miniaturization with the resulting crowding of wires on the backs of panels on which electrical components are mounted.

By the foregoing, the invention has been particularly described in connection with a connector clamp 3 formed of a single strip of sheet metal. It should be obvious that the plate members 6, 7 and 20 may be formed of individual plate elements joined together along a common edge to form the equivalents of the apexes 8 and 9. It should also be noted that although an aperture 19 has been described in the metal connector bar 2 the provision of such aperture is not essential since the clamp may be connected to the bar member 2 at such an angle that the end of the wire 1 does not have to pass through any portion of the connector bar 2. However, the use of the aperture 19 in some instances may be preferred since it minimizes the tendency of the end of the wire 1 to be deformed away from the end 12 of the clamping plate 7 as the clamp is applied.

In the modified form illustrated in FIG. 3 the two outer legs 6 and 7 are curved with their concave surfaces facing the central leg 20. This results in reduction of the screw travel and in reduction of the length of the stripped portion of the wire.

While a particular embodiment of a wire connector clamp employing this invention has been shown and described, it will be obvious that changes and modifications can be made without departing from the spirit of the invention and the scope of the appended claims.

What is claimed as new and desired to be secured by Letters Patent of the United States is:

1. A wire connector clamp comprising a first plate member, a second plate member secured at one edge of said first plate member and forming a first acute dihedral angle with one surface of said first plate member, a third plate member secured to said one edge of said first plate member and forming a second acute dihedral angle with the opposite surface of said first plate member, said first plate member having a wire receiving aperture at a point displaced from said one edge a distance such that said second and third plate members will partially overlie said wire receiving aperture when said second and third plate members are brought into juxtaposition with said first plate member, and means for bringing said second and third plate members into juxtaposition with said first plate member with a wire in said wire receiving aperture whereby said wire is clamped to said wire connector 50 clamp.

45

2. A wire connector clamp as defined in claim 1 wherein said first, second and third plate members each have a fastener receiving aperture for receiving said means.

5 3. A wire connector clamp as defined in claim 2 in combination with a wire connector having an internally threaded aperture wherein said means is a headed fastener having a threaded shank passing through said fastener receiving apertures to engage said threaded aperture.

10 4. A wire connector clamp comprising an elongated member folded to a generally psi-shaped cross-section, said member when folded having two inner legs with wire receiving apertures passing through both of said legs, two outer legs with the ends of said legs extending partially over said aligned wire receiving apertures when all of said legs are brought into juxtaposition, and means for bringing said inner and outer legs into juxtaposition with a wire in said wire receiving aperture whereby said wire is clamped to said wire connector clamp.

15 5. A wire connector clamp as defined in claim 4 wherein said inner and outer legs have fastener receiving apertures for receiving said means.

6. A wire connector clamp as defined in claim 5 in combination with a wire connector having an internally threaded aperture wherein said means is a headed fastener having a threaded shank passing through said fastener receiving apertures to engage said threaded aperture.

20 7. A wire connector clamp as defined in claim 6 wherein said two inner legs form a single plate.

25 8. A wire connector clamp comprising a central leg, a pair of curved outer legs joined to one edge of said central leg with their concave faces toward said central leg and forming acute angles therewith, said central leg 35 having a wire receiving aperture at a point displaced from said edge a distance such that said curved legs will partially overlie said wire receiving aperture when said curved legs are brought into face to face contact with said central leg and means for bringing said central and outer legs into face to face contact with each other with a wire in said wire receiving aperture to effect clamping of said wire to said clamp.
